UNITED STATES PATENT OFFICE.

CAMPBELL C. CARPENTER, OF NIAGARA FALLS, NEW YORK, ASSIGNOR TO U. S. LIGHT & HEAT CORPORATION, OF NIAGARA FALLS, NEW YORK, A CORPORATION OF NEW YORK.

METHOD OF PREPARING STORAGE-BATTERY SEPARATORS.

1,398,065.

Specification of Letters Patent.

Patented Nov. 22, 1921.

No Drawing.

Application filed February 14, 1921. Serial No. 444,736.

To all whom it may concern:

Be it known that I, CAMPBELL C. CARPENTER, a citizen of the United States, residing at Niagara Falls, in the county of Niagara and State of New York, have invented new and useful Improvements in Methods of Preparing Storage-Battery Separators, of which the following is a specification.

10 The present invention relates to methods of preparing storage battery separators.

Various means have been devised for separating the plates in a storage battery cell. Wood separators are commonly used for this 15 purpose, but most woods, which are suitable for the purpose, contain certain substances which in service react with the lead in the cell in a harmful way. Various methods have been devised for treating wood to eliminate or minimize this harmful effect.

20 An object of the present invention is to devise a method for removing harmful constituents from wood, which method will be effective and cheap.

25 A further object is to provide a method for treating wood in the preparation of separators which will not weaken the structure of the wood.

30 Other objects will appear as the description proceeds.

According to the present invention, pieces 35 of wood which have been cut substantially to the thickness required for storage battery separators, are treated with a solution of lead compounds whereby those substances in the wood which attack lead may have an opportunity to combine with the lead in this solution. In order that the solution may more readily come in contact with the substances referred to, it is preferable that the wood be given a preliminary treatment to open the pores. This preliminary treatment 40 may be accomplished by soaking the wood in water, or by treating with steam, for a sufficient length of time to open the pores.

45 There are a great number of soluble lead compounds which may be used, as for instance, lead fluosilicate, lead chlorid, sodium plumbate, and many others. The solution 50 may be used hot or cold, depending upon the nature of the lead salt used, as certain lead salts will, of necessity, have to be used hot

in order to keep same in solution. The combinations formed by the chemical reaction may be washed from the wood with water, after which said wood is ready for service as a storage battery separator.

Instead of using a liquid as the carrier of the lead salt, humid steam may be used. 55 Pieces of wood may be stacked in a steam chest with lead compounds in powdered form or paste form placed between said pieces of wood. The wood, with the lead compounds, will be enveloped in an atmosphere of humid steam, which will open the pores of the wood and dissolve the lead compounds. Said lead compounds will combine with those constituents of the wood which attack lead, the resulting products of which combination will trickle away from the 60 wood. The separators may then be removed and are ready for use.

According to another modification, the wood may be subjected to water or steam, 65 thus opening up the pores, then treated with lead compounds in powdered or paste form, and while kept in a moist condition, exposed to the air, whereby the lead compounds will react with those constituents of wood that attack lead. The resulting compounds may 70 then be removed in any preferred way, for instance, by washing with water or by treating with steam.

Many modifications of the present invention will occur to those skilled in the art. It 75 is intended in this patent to cover all such modifications that come within the scope of the invention as defined by the appended claims.

What I claim as new and desire to secure 80 by Letters Patent of the United States, is:

1. The method of preparing storage battery separators which consists in treating wood with a lead compound.
2. The method of preparing storage battery separators which consists in treating wood to open the pores thereof and subjecting said wood to a soluble lead compound to permit the substances in the wood which attack lead to combine with the lead in said 95 solution.

In witness whereof, I have hereunto subscribed my name.

CAMPBELL C. CARPENTER.
